CALCULATING MACHINE

Conrad Lutropp, East Orange, N. J., assignor
of one-half to Anders Lindahl, Stockholm,
Sweden

Application March 30, 1932, Serial No. 601,975
In Sweden August 21, 1929

11 Claims. (Cl. 235—62)

This application is a continuation in part of my copending application Serial No. 413,294, filed December 11, 1929.

The invention relates to calculating machines and more particularly to mechanism for operating the same. Still more particularly the invention relates to calculating machines of the ten-key type and, further, to calculating machines of such type having a rotary selector and in which 10 energy is supplied to a plurality of rotatable shafts which are rotated in progression.

The principal object of the invention is to provide what may be termed a drive for calculating machines, and more particularly the specific type 15 above referred to, wherein the source of energy involves rotary motion, continuously in one direction, in which shafts are rotated with intermittent motion, and which does not involve special gears, which will provide ease of operation, minimum 20 of torque, minimum of backlash, and yet will give the desired intermittent and progressive actuation.

The invention, its nature, further objects and advantages will be apparent from the following 25 description taken in conjunction with the accompanying drawings forming a part of this specification, of which:

Fig. 1 is a top view, partly in section, of a calculating machine embodying the invention;

Fig. 2 is a side view of the machine broken open and showing internal parts;

Fig. 3 is a view taken generally on the line 3—3 of Fig. 2;

Fig. 4 is a side view taken on the line 4—4 of 35 Fig. 1;

Fig. 5 is a view taken on the line 5—5 of Fig. 3 showing the major parts of the drive;

Fig. 6 is a cross-sectional view through part of the driving mechanism, taken on the line 6—6 of 40 Fig. 5;

Fig. 7 is a view taken on the line 7—7 of Fig. 5;

Fig. 8 is a view taken on the line 8—8 of Fig. 5;

Fig. 9 shows a detail;

Fig. 10 shows a modified drive mechanism, the 45 view corresponding to Fig. 5;

Fig. 11 is an end view of the mechanism of Fig. 10 looking in one direction; and

Fig. 12 is an end view of the mechanism of Fig. 10 looking in the other direction.

50 The principal parts of the machine consist of a keyboard 1, an operating handle 2, a rotary selector 3 movable step by step, a rotatable transfer or counting drum 4, transfer or counting spindles 5 cooperating with the selector and the transfer drum, an indicator 6 for indicating the number

set up, and a carriage 7 carrying the main counting register or totalizer 9.

The keyboard 1 (Figs. 1 and 2) contains ten keys, 10 to 19, corresponding to the digits 0 to 9, respectively, two tabulator keys 20 and 21 for moving the totalizer carriage step by step to the right or to the left, a key 22 for setting the machine for addition or multiplication, a key 23 for setting the machine for subtraction or division, a key 24 which is held in depressed position in repeating 65 the same number set up, as for instance, in multiplication or division, and thereby prevents the resetting of the selector and the transfer spindles to their normal positions, and a key 25 by means of which a numeral erroneously struck 70 on any of the digit keys 10 to 19 may be corrected by returning the selector step by step.

The framework of the machine comprises three horizontal plates 26, 27, and 28, which are attached laterally to the side walls 29 and 291 of 75 the machine casing. The operating handle 2 is journaled in the right-hand wall 29 (Figs. 1 and 7) and is constructed and arranged to rotate shaft 2a continuously in one direction. Instead of a manual handle, an electric motor or other power 80 source may be used for turning the shaft 2a. On the inner end of shaft 2a is rigidly mounted a cam disc 30. Two gear wheels 31 and 33 are rigidly and eccentrically mounted on disc 30 by means of pins 34 and 35. Journaled in the right-hand 85 wall 29 are two shafts 32 and 42. The shaft 32 may be termed the item transfer shaft. The shaft 42 may be termed the tens-carrying shaft.

Disc 30 is connected with the two shafts 32 and 42 as follows: Axially between gears 31 and 33 90 and rigidly held thereto by the pins 34 and 35 is a disc 36. Disc 36 may be integral with gear 31. A link 37 encircles disc 36 and is rotatably mounted on a floating pin or axle 38. Another link 39 is mounted on floating pin 38 and is loosely 95 mounted on shaft 32. A gear 40 is fixedly mounted on shaft 32. An intermediate gear 41 is mounted on pin 38. The gears 31, 41 and 40 are in constant mesh. The pin 38 may be fast in one of the three members 37, 39, and 41, but must 100 be loose with respect to the other two members. The gears 31 and 40 are of the same size, whereas the intermediate gear 41 is larger.

Pin 35 has an end collar 47. Adjacent this collar and surrounding the pin is a link 43. Link 43 also surrounds a floating pin or axle 44. A link 45 connects pin 44 with shaft 42. Mounted on shaft 42 is a gear 46. Gear 46 is rigidly mounted on shaft 42, whereas link 45 is loosely mounted 105 110

thereon. An intermediate gear 48 meshes with gears 33 and 46.

Gear 48 is of the same size as gear 41. Gears 31, 33, 40, and 46 are of the same size. Pin 44 5 may be secured rigidly in one of the three parts 43, 45, and 48, but it must be loose with respect to the other two.

Before describing the remainder of the machine, which in general is similar to what is disclosed in my earlier Patent No. 1,662,526, granted March 13, 1928, I will describe the operation of the driving mechanism. As will be apparent from a consideration of my aforesaid Patent No. 1,662,526, shafts 32 and 42 (numbered the same in 10 my aforesaid patent) shall be driven in such manner that shaft 32 first rotates substantially a complete revolution while shaft 42 is stationary, and then shaft 32 stops or has but little movement while shaft 42 rotates a complete revolution.

20 The handle 2 is in normal position when the handle lever extends downwardly from the handle shaft. If desired, a spring-pressed ball or other catch mechanism may be provided to define idle position of the handle and hold the handle 25 against slight force. The handle 2 is rotated in clockwise direction looking toward the right-hand side of the machine as shown in Fig. 1. That is, the handle being down, it is first pulled toward the operator and continued around through a 30 complete revolution. This is indicated by the arrow on the shaft 2a in Fig. 5, which shaft is attached to the handle. Rotation of shaft 2a in clockwise direction causes rotation of disc 30 in clockwise direction. Fig. 5 shows idle or starting 35 position. It will be seen that at the beginning of the rotation the eccentrically mounted gears 31 and 33 will be bodily moved to the right. This will move the link 37 to the right and downwardly and then to the left and consequently swing the 40 link 39 somewhat to the right and then to the left whereby the link members are straightened somewhat and the net result is a movement of link 39 to the left so that it moves in counter-clockwise direction about the shaft 32. At the 45 same time, the gear 31 is rotated in clockwise direction and causes rotation of gears 41 and 40 as a result of which shaft 32 is rotated in clockwise direction. Due to the arrangement of gears and linkage, the rotation is amplified and by the time 50 the shaft 2a has rotated 180 degrees, the shaft 32 has rotated substantially 360 degrees.

In the meanwhile, the gear 33 is moved, but this gear, at the start, tends to rotate gear 46 in clockwise direction while link 45 is moved in counter-clockwise direction whereby the movement is neutralized. It will be seen that in starting position the line between the center of shaft 2a and pin 44 is at slightly less than a right angle to a line between the center of shaft 42 and pin 44. The link 43 swings through right-angle position and slightly beyond the same before there is any appreciable rotation of gear 46 by gear 33. The net result is that while the shaft 2a rotates through 180 degrees, the shaft 32 rotates through substantially 360 degrees while the shaft 42 remains substantially stationary.

After movement of shaft 2a through 180 degrees so that the handle 2 is up, the shaft 42 is rotated because the links 43 and 45 fold together and the gear 33 moves toward the gear 46, the folding of the links and the rotation being cumulative due to the opposite relations of these links to the other links 37 and 39. During this period the folding of the links 37 and 39 substantially neutralizes the rotation of the gear

wheels in the right-hand gear train, and shaft 32 remains substantially stationary.

It will be noted that two gear wheels 31 and 33 are employed which are eccentrically mounted on disc 30. Instead of this, one gear may be employed, but the two gears give a slightly greater period of rest with respect to motion for the respective shafts. If one gear is used instead of two, it will mesh with both the gears 41 and 48. In using a single eccentric gear, it is preferable to use less than the number of spindles shown in Fig. 1, the parts remaining the same, since there is more overlap of motion with one eccentric gear.

It will be seen that the reciprocating motion of the gears of the gear trains is so related to the rotation as to hasten and decrease the rotation, respectively, whereby, although the driving shaft rotates at constant speed, each of the driven shafts is intermittently rotated and while one driven shaft is at rest, the other is rotating. To accomplish the best results, the gear wheels 41 and 48 should be larger than the driving and driven gear wheels and the arrangement should be such that the driving and driven gears rotate to positions as close to each other as possible.

On the inner end of the shaft 32 a bevel gear wheel 450 (corresponding to gear wheel 45 in my aforesaid Patent No. 1,662,526) is secured, which alternatively engages two other bevel gear wheels 460, 470, which are loosely mounted on a vertical 105 shaft 480. Between the gears 460, 470 a clutch coupling is provided in the same manner as described in my aforesaid patent. This clutch is operated by the keys 22 and 23.

The selector 3 is loosely journaled on the shaft 110 480 while the transfer drum 4 is rigidly secured to said shaft. The counting or transfer spindles 5 are disposed around the selector and the transfer drum. Normally, the counting spindles are held in their lower positions by a half circular 115 flange ring 65 supported by vertical guides 66 (Figs. 3 and 4) which pass through corresponding guide openings in the frame plates 26 and 27 and at the top are connected with levers 67 rigidly secured to a shaft 68. The means for operating 120 the flange ring 65 consists of a link 69 connected to one (the right in Fig. 3) lever 67. Link 69 has near its lower end a notch 70 (Fig. 4) engaged by the hooked end of a catch lever 71 journaled on the pin 72 secured in the end of a lever 73 which 125 is pivoted on the casing at 210. The catch lever 71 is connected, by means of a link 74, with a pivotally mounted bell crank lever 75 which is engaged by the key 24 so that the coupling between the link 69 and the lever 73 can be released, when 130 desired, by depressing the key 24. When the catch lever 71 is released, the lever 73 can move freely in relation to the link 69, but the parts 73 and 69 are, in such case, maintained in restricted 135 relation to each other by means of a pin 76 on lever 73 which enters and moves in an oblong opening 77 in the lower end of link 69.

The selector 3 is of the same construction as that set forth in my aforesaid patent, and further description thereof is here unnecessary.

Likewise the construction of the drum 4 is the same as in my aforesaid patent and further description thereof is unnecessary, it being understood that with respect to matters not changed by this disclosure, the description and illustrations 145 of my aforesaid patent are to be considered as incorporated in this disclosure.

The member 65 must be released before the transfer of items takes place and must be moved downward into locking position before the selector 150

is returned to idle position. This is accomplished by means of the cam disc 30. As is shown in Fig. 5, this disc has an outer cam surface comprising substantially one-half the circumference thereof of a given diameter and the remainder of a different given diameter. The outside cam surface of disc 30 contacts a roller or projection 200 on a member 201 which is guided by shaft 2a by means of a slot 202 and which is connected to lever 73. In idle position as shown in Fig. 5, disc 30 holds lever 73 down, whereby, tongue 71 being in notch 70, member 65 is held down. Shortly after handle 2 has been rotated, the part of the cam surface of disc 30 of lesser diameter comes into contact with roller 200 and lever 73 and member 65 are permitted to rise under the influence of tension springs 203 and 204. The lever 73 and member 65 remain in elevated position until disc 30 has completed half a revolution when the cam surface moves radially outwardly and lever 73 and member 65 are returned to lowered position. Thus lever 73 is raised while shaft 32 is rotated for the transfer of items to the totalizer and is lowered when the shaft 42 is rotated and the selector returned to initial position.

It will be understood that when catch 71 is out of recess 70 due to depression of key 24, lever 73 will travel freely up and down under the influence of spring 204 and controlled by cam 30. In such case, lever 73 will not affect ring 65 and the transfer spindles.

The resetting of the selector to idle position is effected by means of a rack 101 of the same construction as disclosed in my aforesaid patent. The rack 101 is adapted to be moved rearwardly by means of a pawl 108 having a projection 110 adapted to engage the forward end of the rack. Pawl 108 is connected by means of a pin 105 to a link 104 and the pin 105 is guided in a slot 106 in the slotted link 107, as by a flanged roller. The pawl 108 is adapted when moved to forward position to engage the rack 101 and move the same rearwardly. In order to obtain forward and backward movement of the link 104, this link is pivoted to a link 109 in turn pivoted to the frame at 111 and also pivoted to a link 112 which is pivoted at 113 on an upward extension of the link 45. When the upper end of the link 45 moves forwardly, the link 112 moves forwardly and causes links 109 and 104 to move forwardly, whereby pawl 108 is moved forwardly. When the link 45 moves back, the selector is carried back with it.

Thus it will be seen that the resetting of the selector and the resetting of the counting or transfer spindles is accomplished at substantially the same time as in my aforesaid Patent No. 1,662,526, these actions being obtained from the reciprocating movement of the link 45 and the disc 30.

With respect to the remainder of the machine, it is the same as that disclosed in my aforesaid patent, wherefore it is not necessary to describe it. Some reference characters have been applied which correspond to the parts in the aforesaid patent. It will be understood that the shaft 32 is first rotated, in turn causing rotation of the counting spindles whereby the items set up are transferred through shafts 122 to the totalizer. When this transfer has taken place, the selector and transfer mechanism are returned to idle or normal position and the transfer of tens takes place by rotation of the shaft 42. It will be understood that there may be a certain amount of overlap and play in the movements of the parts.

The tens-carrying mechanism is of the same

construction as in my aforesaid patent including the shafts 162, 163 and the projecting fingers 164 and 165.

In Figs. 10, 11 and 12 I have shown another embodiment of the drive mechanism of the invention. Like reference characters are used for corresponding parts. In this embodiment the linkages are expanded or stretched in initial position. The handle is down in initial position. The handle in this case is rotated in the opposite direction with respect to the embodiment shown in Fig. 5. This is indicated by arrows in Fig. 10, which is a view corresponding to Fig. 5. A single gear wheel 313 replaces the two gears 31 and 33. Gear 313 is eccentrically mounted on disc 30 which may be provided with a cam surface as in Fig. 5.

In this embodiment, at the beginning of rotation, gear 313 is moved bodily to the right. This moves links 37 and 39 to the right as gear 313 approaches gear 40. Due to the planetary motion of gear 313, the rotation is amplified and shaft 32 moves through substantially 360° while shaft 2a moves through 180°. During this period, shaft 42 has substantially no movement. During the remaining half-turn of shaft 2a, shaft 42 moves while shaft 32 remains substantially stationary.

It will be seen that in this embodiment shafts 32 and 42 move in the opposite direction from the previously described embodiment. This can readily be taken care of by merely reversing the addition and subtraction keys while retaining the same structure and by omitting or adding a gear in the train between shaft 42 and the tens-transfer mechanism.

The handle can be made to rotate in the opposite direction by interposing gears between the handle and shaft 2a.

It will be seen that I have accomplished the drive of the machine without the use of elliptical or other special gears. Also, it will be seen that this drive is readily adaptable to electric motor operation.

It will be evident that various departures may be made from the structure above described.

What I claim is:

1. In a calculating machine having item transfer mechanism, tens-carrying mechanism, a first shaft for operating the item transfer mechanism, and a second shaft for operating the tens-carrying mechanism; a rotatable drive shaft, and means for alternately rotating said first shaft and said second shaft during a revolution of said drive shaft comprising a first gear train between the drive shaft and the first shaft including a floating gear, a second gear train between the drive shaft and the second shaft, and means for maintaining the gears constantly in mesh.

2. In a calculating machine having item transfer mechanism, tens-carrying mechanism, a first shaft for operating the item transfer mechanism, and a second shaft for operating the tens-carrying mechanism; a rotatable drive shaft, and means for alternately rotating said first shaft and second shaft during a revolution of said drive shaft comprising articulated gear trains.

3. In a calculating machine having item transfer mechanism, tens-carrying mechanism, a first shaft for operating the item transfer mechanism, and a second shaft for operating the tens-carrying mechanism; a rotatable drive shaft, and means for alternately rotating said first shaft and said second shaft during a revolution of said drive shaft comprising articulated gear trains each including an eccentrically mounted initial gear, final gears, intermediate gears and links

therebetween, said intermediate gears being displaced in opposite direction with respect to the initial and final gears respectively on rotation of the drive shaft.

5 4. In a calculating machine having a selector, item transfer mechanism, means to actuate the selector, and means for returning the selector to idle position; drive mechanism including a plurality of gears and links for holding the gears 10 in mesh, at least one of said gears being eccentrically mounted whereby the links are moved, and means responsive to movement of one of said links for actuating the selector return mechanism.

15 5. In a calculating machine having a selector, item transfer mechanism, means to actuate the selector, and selector return mechanism for returning the selector to idle position including a rack and a pawl engageable with said rack; drive 20 mechanism including a plurality of gears and links for holding the gears in mesh, at least one of the gears being eccentrically mounted whereby the links are moved, and mechanism interconnecting said pawl with one of said links.

25 6. In a calculating machine having a plurality of item transfer members, setting means to set said members for transfer of items, and means to reset said members; drive mechanism including a cam disc, plurality of gears and links for holding the gears in mesh, at least one of said gears being eccentrically mounted with respect to said cam disc whereby the links are moved, and means responsive to movement of said cam disc for operating the resetting mechanism.

35 7. In a calculating machine having a plurality of item transfer spindles, setting means for setting said spindles for transfer of items, means to reset said spindles including a ring member, and means including a lever for moving said ring 40 member; drive mechanism including a cam disc, a plurality of gears and links for holding said gears in mesh, at least one of said gears being eccentrically mounted on said cam disc whereby the links are moved, and means responsive to movement of said cam disc for actuating said lever.

50 8. In a calculating machine having a selector, item transfer members, key mechanism for stepping the selector, means for returning the selector to idle position, and means for moving the item transfer members; drive mechanism including a cam disc, a plurality of gears and links for holding the gears in mesh, at least one of said gears being eccentrically mounted with respect to said cam disc whereby the links are moved, and means responsive to movement of one of said links and

said cam disc for actuating the first-mentioned and the second-mentioned means.

9. In a calculating machine, a driving shaft, a plurality of gears eccentrically mounted on said shaft, a first driven shaft for transfer of items, a second driven shaft for carrying of tens, a first pair of links having a loose joint and mounted coaxially with the first driven shaft and one of the eccentric gears, and a second pair of links having a loose joint and mounted coaxially with the second driven shaft and another of the eccentric gears, gears on the driven shafts, intermediate gears mounted on the loose joints, the gears associated with each pair of links being in constant mesh, and the eccentricity and linkage being such that lines between the link centers of the respective pairs pass through right-angle relationship on a revolution of the driving shaft.

10. In a calculating machine, a driving shaft, a plurality of gears eccentrically mounted on said shaft, a first driven shaft for transfer of items, a second driven shaft for carrying of tens, a first pair of links having a loose joint and mounted coaxially with the first driven shaft and one of the eccentric gears, and a second pair of links having a loose joint and mounted coaxially with the second driven shaft and another of the eccentric gears, gears on the driven shafts, intermediate gears mounted on the loose joints, the gears associated with each pair of links being in constant mesh, the eccentricity and linkage being such that lines between the link centers of the respective pairs pass through right-angle relationship on a revolution of the driving shaft, 100 and the links of the respective pairs being angularly disposed in opposed relationship.

11. In a calculating machine, a driving shaft, a plurality of gears eccentrically mounted on said shaft, a first driven shaft for transfer of items, a second driven shaft for carrying of tens, a first pair of links having a loose joint and mounted coaxially with the first driven shaft and one of the eccentric gears, a second pair of links having a loose joint and mounted coaxially with the second driven shaft and another of the eccentric gears, gears on the driven shafts, and intermediate gears mounted on the loose joints, the gears associated with each pair of links being in constant mesh, the eccentricity and linkage being such that lines between the link centers of the respective pairs pass through right-angle relationship on a revolution of the driving shaft, the first-mentioned gears and the gears on the driven shafts being of the same diameter and the intermediate gears being larger.

CONRAD LUTTROPP.

130
